UNITED STATES PATENT OFFICE.

GERGELY BALOGH, OF DETROIT, MICHIGAN.

LIFE-SAVING SUIT.

1,211,042.

Specification of Letters Patent.

Patented Jan. 2, 1917.

Application filed August 9, 1916. Serial No. 113,922.

To all whom it may concern:

Be it known that I, GERGELY BALOGH, a subject of the King of Hungary, residing at Detroit, in the county of Wayne and State 5 of Michigan, have invented certain new and useful Improvements in Life-Saving Suits, of which the following is a specification.

This invention relates to certain new and useful improvements in life saving suits.

10 The primary object of the invention is the provision of a water-proof suit adapted to be readily put on by a person for preventing the clothing from becoming wet when swimming in the water, an adjustable float being 15 secured to the suit preventing the drowning of the wearer.

A further object of the device is the provision of a water-proof suit having an encircling pneumatic float arranged thereon at 20 substantially the waist-line and being vertically adjustable for maintaining the equilibrium of the wearer when in a floating position in the water, a keel member being arranged for assisting in maintaining a forward course 25 of travel during the paddling operation.

With these general objects in view and others that will appear as the nature of the invention is better understood, the same consists in the novel construction, combination 30 and arrangement of parts hereinafter more fully described, illustrated in the accompanying drawings, and then claimed.

In the drawings forming a part of this application and in which like designating 35 characters refer to corresponding parts throughout the several views:—Figure 1 is a front elevation of a person provided with the present device illustrated in the act of inflating the float member. Fig. 2 is a central radial horizontal sectional view of Fig. 40 1 through the float member. Fig. 3 is a side elevational view of the central portion of the device partially broken away, and, Fig. 4 is a vertical sectional view taken upon line 45 IV—IV of Fig. 2.

The present device broadly consists of a suit 10 formed of water-proof material and adapted to be worn over the clothing of the person completely enveloping the latter excepting the neck and head, the said suit being arranged with an adjustable encircling pneumatic float 11.

The suit 10 is arranged with boot portions 12 for the feet and with glove portions 55 13 for the hands of the wearer while the

shoulder portions of the suit are divided as at 14 having connecting shoulder straps 15 for retaining the suit upon the person when operatively arranged.

The float 11 is of circular tubular form 60 preferably made of rubber and having an air entrance tube 16 for inflating the same, a valved mouth-piece 17 being provided for the said tube whereby the wearer may blow air through the tube 16 into the float 11. A 65 further pipe 18 is also provided for the float 11 having a valve 19 being designed for allowing the air to escape from the float as well as to be filled from any form of air compressor.

70 The float 11 is provided with horizontally arranged strengthening cords 20 and similar vertically positioned cords 21 intermediately arranged within the float. A hollow tail or rudder portion 22 is provided at the rear of 75 the float 11 communicating with the interior thereof, the said rear portion being formed of two sections 23 oppositely positioned and downwardly tapering, providing parallel keels 24 arranged within the 80 water beneath the level of the float 11 when the float is positioned upon the water. The arrangement of the keel members is best illustrated in Figs. 3 and 4 of the drawings, the same acting as a rudder for normally 85 maintaining a direct forward course when the wearer of the suit 10 is paddling with his hands.

89 Depending straps 25 are carried by the float 11 having button-holes 26 adapted for 90 engaging desirable ones of a plurality of series of buttons 27 circumferentially positioned upon the suit 10 and at substantially the waist line thereof. The float 11 in this manner may be secured at the desired height 95 upon the suit to accommodate the wearer and maintain the proper equilibrium when positioned in the water.

What I claim as new is:

1. A life saving apparatus comprising a 100 suit having a plurality of series of circumferentially arranged buttons adjacent the waist-line thereof, an encircling pneumatic float removably attached to the said buttons in its adjusted operative position, and an 105 inflated double keel portion provided at the rear of the float depending therebeneath.

2. A device of the class described comprising a water-proof suit adapted for enveloping the person, an encircling pneu- 110

matic float adjustably attached to the said suit and at substantially the waist-line thereof, diametrically arranged reinforcing cords secured within the said float, and a rearwardly-extending divided rudder portion 5 carried by the said float with the interior thereof in communication with the pneu-

matic chamber of the float and arranged with depending downwardly converging parallel keel portions extending beneath and 10 rearwardly of the said float.

In testimony whereof I affix my signature.

GERGELY BALOGH.
